USE OF NAPHTHA REFLUX

Stephen E. Freeman, Pittsburgh, Pa., assignor to
 Pittsburgh Plate Glass Company, Allegheny
 County, Pa., a corporation of Pennsylvania

Application June 22, 1948, Serial No. 34,453

7 Claims. (Cl. 260—428.5)

1

The present invention relates to the fractionation of glyceride oils with selective polar solvents such as furfural, designed to effect separation of such components as the more unsaturated glycerides and free fatty acids, sterols, inhibitory, etc.

One object of the invention is to provide a process whereby a fraction of glycerides of substantially higher iodine value than is conventionally obtained by solvent fractionation is separated.

A second object is to reduce the viscosity of the oil-solvent mixture undergoing extraction.

A third object is to improve the output of the apparatus employed in effecting the fractionation.

A fourth object is to obtain a fraction of glyceride oil of exceptionally high iodine value in which the formation of polymers of oil or solvent and other phenomena is reduced to a minimum.

A fifth object of the invention is to obtain oils of improved iodine value as above described in a highly economical manner.

A sixth object of the invention is to obtain a fraction of a glyceride oil which is of exceptionally high iodine value but is low in color, free fatty acids and other impurities.

A seventh object of the invention is to obtain a more saturated fraction of glyceride oil, low in color and free fatty acids and which is more desirable for conversion into good products than the original oil.

These and other objects of the invention will be apparent from consideration of the following specification and the drawings.

In the drawings, Figs. 1 and 2 are diagrams or flow sheets illustrating two slightly different forms of apparatus that can be used in producing the invention.

It has heretofore been recognized that natural glyceride oil such as soybean oil, linseed oil, cottonseed oil and others include as their main constituent glycerides of higher fatty acids notably saturated acids on the one hand such as palmitic acid, and stearic acid and unsaturated acid on the other hand such as oleic acid, linoleic acid, linolenic acid and others in minor proportions. It is understood that the acid radicals tend to assume uniform distribution in the glyceride molecules, that is, most of the molecules will comprise a mixture of two or more of the fatty acids. However, some of the glyceride molecules do actually possess a higher degree of unsaturation than the others.

In accordance with my prior Patents 2,200,391 and 2,200,390 and my copending applications Se-

2

rial No. 335,005 of May 13, 1940, now abandoned, and Serial No. 705,807 of October 25, 1946, now abandoned, of which the present application is a continuation-in-part, it is found that the glycerides of higher degree of unsaturation can be successfully separated from those of higher degree of saturation by contacting the glyceride oils in liquid phase with certain polar solvents such as furfural. In this manner it is possible to separate from many of the oils and notably the drying or semi-drying oils such as soybean oil, considerable amounts of glycerides of highly unsaturated character well adapted for use in the formulation of paints and varnish which are adapted to air dry, or in the production of air-drying alkyd resins which are then further adapted for use in the coating industry.

In order further to improve the iodine value of the extracted oil so obtained, it has been proposed to reflux or recycle a part of the extract oil after extraction and partial or complete removal of the furfural, to the lower zones of the extraction column. This refluxing results in important improvements in the iodine value of the extracted oil. However, it is found that by application of such technique there is also a tendency to build up the concentration of coloring matter, anti-oxidants and other objectionable constituents in the extract. This tendency is particularly pronounced if small extract yields are to be taken.

The present invention contemplates an improvement upon the simple technique involved in merely contacting the oil with a selective polar solvent and then separating the resultant phases and evaporating off the solvents to obtain the more saturated and less saturated components of the oils as separate fractions. More specifically the invention resides, as one step, in the employment of naphtha as a reflux which is added to the lower portions of the extraction zone containing oil and furfural in a counter-current column, in such amount and under such conditions that the iodine value of the extracted oil obtained from the lower portion of the column is greatly improved, there being a substantially sharper separation of the more unsaturated glycerides from the more saturated glycerides. As a second step, the invention comprises backwashing the extract solution of glyceride oil containing by-products such as natural coloring matter, sterols, free fatty acids, tocopherol and other anti-oxidants, etc. with naphtha to remove nearly all of the glycerides, but leaving the by-products, then recovering the glycerides from the naphtha as a refined, high iodine fraction. By application of this tech-

nique, a high iodine value extract product is obtained and at the same time, there is substantially less tendency to carry back into the extraction system coloring matter and other by-products which are objectionable in the extract product.

In the practice of the invention, a glyceride oil such as soybean oil, linseed oil, cottonseed oil, corn oil, sardine oil, peanut oil or the like, that contains glycerides, at least some of which contain one or more fatty acid radicals which are olefinically unsaturated and preferably some of which are di- or even tri-olefinically unsaturated along with by-products as mentioned, is subjected to counter-current extraction with a polar solvent such as furfural in a column. Simultaneously, a reflux of naphtha is introduced near the bottom of the extraction zone. This reflux is usually small, about .1 to .5 the volume of feed oil, but in those cases where the ratio of polar solvent such as furfural to oil is high, the volume of reflux may be increased in the manner illustrated in certain of the subsequent examples. A polar solvent (furfural) solution of the more highly unsaturated components of the oil, is taken off at the bottom of the system and a solution of more highly saturated or completely saturated oils containing most of the naphtha is taken off at the top of the extraction zone.

As a feature of the invention, the extract solution of glyceride oil and by-product is re-extracted with a larger volume of petroleum naphtha than that used as reflux, to take out the fraction of more unsaturated glycerides. The petroleum naphtha employed may be any hydrocarbon or mixture of hydrocarbons which is immiscible or but partially miscible with furfural, but preferably is one of relatively high boiling range, e. g. 290 to 370° F., and having a Kauri Butanal Value in the range of 36 to 39. Other naphthas of either higher or lower boiling range are contemplated, and these may include any hydrocarbon which is liquid at the temperature of operation and is not unduly high in boiling range, and which is immiscible or but partially miscible with furfural or other polar solvent employed. This range may include, for example, hexanes and other hydrocarbons through the range of kerosenes. The petroleum naphtha is employed in substantially higher ratio in column 16 than is employed as a reflux in column 10. A good average ratio of naphtha to original feed oil, in column 16, would be about 1 to 3 parts per part of feed oil, e. g. as disclosed in one of the subsequent examples, 2.4 to 1. However, if the proportion of furfural is high, in the extract, the proportion of naphtha feed in column 10 may be increased correspondingly. Obviously, it should not be so increased as to strip out all or substantially all of the free fatty acids.

It is also to be observed that the temperature of column 16 is substantially lower than that of column 10. This differential may be 10 to 60° F., e. g. about 40 or 50° F. The differential of optimum operation will vary for different oils and different ratios of solvents. Lower temperatures in the backwash column 16, favor clean and thorough separation of the glycerides from the furfural phase, since the solubility of the oil in furfural drops rapidly with drop of temperature, while the temperature at least within reasonable limits, does not substantially change the miscibility of the glycerides and naphtha.

There is no particular lower limit of temperature for the backwashing of the furfural solution, except those of economics and the point at which glycerides tend to crystallize out.

5 The naphtha and residual furfural in the naphtha solution can be distilled off to obtain the extract product.

One convenient embodiment of apparatus useful for the practice of the invention is illustrated by the flow diagram in Fig. 1. In accordance with the procedure illustrated in this diagram, glyceride oil such as soybean oil, linseed oil or cottonseed oil, corn oil, peanut oil, sardine oil or the like, is introduced at 11 into an intermediate portion, for example, in a zone somewhere between the upper and lower fourths of the column 10. Polar solvent such as furfural is introduced into the upper part of the column at a point 12. Preferably sufficient space is left above the point of introduction of the polar solvent, to permit the raffinate solution containing naphtha in the clearing section 10-a, top of the column, adequately to separate from the solvent medium before the raffinate phase is drawn off as indicated at 13, say 5 or 10 feet above the point of inlet of furfural, in order to permit the phases to separate before the raffinate is drawn off. All or a part of the space 10-c, between inlets 12 and 14, may be filled with a packing 20 such as Berl saddles, Raschig rings or the like, designed to effect thorough contact of the liquids in the column. The packing may be supported at its bottom by perforated plates and additional plates at appropriate intervals.

35 Non-polar solvent, such as naphtha, which is of lower density than the polar solvent, is introduced near the bottom of the column and at a point substantially below the point of introduction of the oil, for example, at least 10 and 40 preferably 30 or 40 feet below the inlet for the oil. Much more space is permissible. The upper limit is imposed by economics. There should also be a space, 10-b, say 5 or 10 feet or more, at the bottom of the column below the point of introduction of the naphtha, for purposes of permitting the solution of oil and polar solvent adequately to separate from the naphtha before the solution is withdrawn from the bottom of the column, as indicated at 15. An excess of clearing space at the top or bottom, for phase separation, is permissible. A phase interface will usually form at some level between lines 12 and 14.

The furfural solution of high iodine value oil from column 10, may be subjected immediately to distillation to remove furfural, but the solutions preferably are passed to a second packed column 16 for extraction with an excess of naphtha introduced at 17 (1 to 5 volumes based 55 on oil feed) to remove all except an amount equivalent to 0.3% to 1.5% of the original oil and to leave in solution most of the free fatty acids, tocopherols, sterols, chlorophyll and other coloring matter. A clearing section 16-a, say 2 to 10 feet or more, may be left above inlet 15. Naphtha containing an extract of the more highly unsaturated glycerides, passes off at 18. Furfural, containing the by-products, passes off at 19 from bottom clearing section 16-b. A 60 phase interface will usually form at some point between inlets 15 and 17. The solvent from the extract and raffinate solutions may be removed by distillation.

In the operation of a system in accordance 65 with the provisions of the present invention, it is

desirable that the volume of polar solvent be maintained as low as practicable, consistent with the separation of a reasonable proportion of the more unsaturated glycerides. Usually the polar solvent such as furfural, will be employed in a ratio by volume, of approximately 2 to 8 per volume of glyceride oil introduced. However, higher ratios, say 10 to 20 volumes of solvent per volume of oil, are not precluded. It is to be understood that the naphtha reflux is introduced into the extraction column in a lower proportion with respect to the furfural feed, in a proportion of e. g. 1 to 1.5 volumes with respect to the volume of oil. If very large volumes of furfural are employed e. g. 10 to 20 volumes per volume of oil, the ratio of naphtha may be considerably higher, even up to or above 2 to 5.

The temperature of the system is adjusted in such manner that the proportion of oil in the extract from the bottom of the column falls within the limits of 10 to 70% of the total oil. This temperature, of course, will vary with different oils, different solvents and different solvent ratios. For soybean oil, it preferably will be within a range of about 90 to 125° F. Usually the temperature for a given oil at a given solvent ratio, can be determined by heating oil and solvent in desired ratio, to miscibility temperature. Operating temperature for columns 10 or 21 will usually be 10 to 60° F. lower than this miscibility temperature. The temperature may be attained by preheating the glyceride oils or the solvent media before they are introduced into the column, or by the provision of appropriate cooling or heating coils or jackets in conjunction with the column. The application of such devices does not constitute a specific element of the present invention. The temperature may be controlled by heat exchanger 20, supplied with an appropriate medium through lines 20-a.

The raffinate of more highly saturated glycerides drawn off at 13, will be of lower iodine value than the feed oil. Assuming that the initial oil is soybean oil, one of the best for purposes of the present invention, the iodine value will be approximately 110 to 130, dependent upon the feed oil and the manner in which the column is operated. For example, at a given solvent ratio assuming that a large volume of raffinate is desired, the column will be operated comparatively cool, thus assuring that the furfural dissolves a low proportion of the oil. The oil which is dissolved by the furfural or polar solvent, however, will then be of maximum iodine value. If a large extract of moderate iodine value is desired, the temperature can be raised. However, if the temperature is increased to such a degree that the phases within the column become completely miscible, the system becomes inoperative and fractionation impossible.

The raffinates from the column, as drawn out through the line 13, should be appropriately treated in order to eliminate the solvents therefrom. For example, the solvents may be evaporated under vacuum, or steam distilled. The specific technique of distillation is not regarded as being an essential feature of the present invention.

An important feature of the invention resides in the fact that the raffinate or more saturated glyceride oil fraction is refined in the process. The process, as previously described, is adapted to the use of either crude or refined oils as feeds and is especially well adapted to the use of degummed oils such as degummed soya oil. Normally, because of the relatively high acid value

and presence of objectional natural pigments, crude or degummed oils must be alkali refined and bleached for the removal of these objectional constituents before the oil may be processed into food products such as salad oils or hydrogenated products.

In the above process where degummed soya oil is used as the feed oil, the major portion of the free fatty acid and certain objectional pigments, notably the chlorophyll, are removed with the extract fraction, leaving a raffinate relatively free of fatty acid and chlorophyll. The break constituents concentrated in this fraction may be removed by light alkali refining, water degumming or other conventional methods. The raffinate oil produced by this process is therefore refined in respect to free fatty acid and chlorophyll and may be processed into food products in a more simple and economic manner.

Typical data illustrating percentage chlorophyll reduction of a raffinate treated as above described, are as follows:

	Original Oil	Low Iodine Value Oil
25	0.000077	0.000000
	0.00043	0.000056
30	0.00062	0.000050
	0.00012	0.000020
	0.00062	0.000040

The chlorophyll content of the low iodine value fractions is about one tenth that of the original oil. These raffinates of low chlorophyll content can be readily processed to white shortening.

The furfural extract solution from column 10 as obtained from line 15, may be subjected to further naphtha extraction in order to strip out most of the glycerides, leaving in the furfural solution only about 0.3-2.0% of the glycerides, along with large proportion of the free fatty acids, coloring matter, sterols and the like. For this purpose, the extract solution from line 15 is passed to the upper extremity of column 16, which is fed near the bottom thereof, as indicated at 17, with naphtha in a proportion to take out nearly all the oil, e. g. in a proportion of 1 to 5 parts by volume based upon the original oil. The naphtha solution of refined glycerides of high iodine value, is drawn off at the top of the column at 18. The furfural solution, rich in by-products, is taken off at the bottom, as shown at 19. The solutions are stripped by steam or otherwise in stills (not shown).

The extract solution removed at 15 contains, in addition to the high iodine value glycerides, free fatty acids, chlorophyll, ether natural pigments and unsaponifiable matter. By means of naphtha extracting this solution in column 16, a naphtha extract of glyceride oil of improved color and free fatty acid content is obtained. This high iodine value fraction is a break free, varnish grade oil, even though the feed oil may have been a crude or degummed oil.

The by-product solution removed at 19 contains the major portion of the free fatty acids and chlorophyll in addition to other natural pigments, a concentration of the unsaponifiable matter and traces of break constituents.

In a run in the apparatus shown in Fig. 1, soybean oil which had been refined to remove break and being of an iodine value of 132.2, was

furfural extracted. The conditions of the run were:

Oil feed, 30 parts
Furfural (dry), 660 parts, saturated with naphtha at 135° F.
Naphtha reflux, 68 parts
(Parts are by volume.)

The column 10 was at 135° F. The glycerides in the extract solution could be stripped out with naphtha in column 16. An extract product in a yield of 62% of 150 I. V. was recovered. A 38% yield of raffinate iodine value 104, was obtained.

The extract was a good drying oil. The raffinate was a good oil and could easily be hydrogenated to provide a solid fat.

In a further example, soybean oil, iodine value 135.9, was extracted with furfural in column 10. Column temperature at top 108.5 to 110° F.; at the bottom 111.5 to 112° F. The feed rates in parts by volume were:

Soya oil	30
Furfural	90
Naphtha reflux	6

The extract oil could be recovered with naphtha in column 16, at a temperature of 60-80° F.

Results

	Extract	Raffinate	Feed Oil
Weight yield, per cent	23	77	
Iodine Value	154	129.9	135.9

Cottonseed oil could be extracted in similar manner with furfural in column 10. The temperature is at an optimum at about 118° F. but may be 5 to 10 degrees higher or lower. A furfural feed of 3 to 8 parts by volume, e. g. 3 parts based on the feed oil may be employed. A reflux of 1 to 5 parts by volume of naphtha based on the feed oil may be introduced at 11.

The glycerides could be extracted out of the furfural in column 16 using naphtha. The optimum temperature is about 70 to 75° F. The proportion of naphtha based on the feed oil rate may be about 1 to 1.

Linseed oil can also be treated in the same way. The temperature of the column 10 for linseed oil may be about 80° F.

In a further example, break free, or refined soybean oil, iodine value 138 was extracted in column 10.

The column temperature was 90-91° F.

The ratios of the feeds to the column in parts by volume were:

Furfural	200
Feed oil	40
Naphtha reflux at bottom of column	12

In column 16, the temperature was maintained within a range of 50 to 80° F.

Results

	Extract	Raffinate	Original
Weight Yield, per cent	26	74	128.3
Iodine value	163.5	129.7	128.3

In a second run, using the apparatus shown in Fig. 1, degummed soybean oil of iodine value 133.5 and 0.25 per cent free fatty acid was extracted with furfural. Degumming may be by hydration as described in the text, "Industrial

Oil and Fat Products," A. E. Bailey, Interscience Publishers, 1945, page 501. Column 10 was at a temperature of 112.5° F. at the top and 115° F. at the bottom. Column 16 was at a temperature of 70° F.

Proportions in parts by volume:

Furfural	75
Oil	15
10 Naphtha reflux at 14	5
Naphtha backwash at 17	27

Practically all of the glycerides could be extracted out of the furfural phase by application of naphtha in column 16, at a temperature about 40° F. below that in column 10.

Results

	Extract	Raffinate	By-Product
Per Cent Yield	31.8	67.5	0.7
Iodine value	155.8	123.0	
Color	good	good	black
Per Cent Free Fatty Acid	0.036	0.061	

The following constitute specific constructions and operational data for a commercial operation, using the invention as illustrated in Fig. 1:

30

A. Primary column 10

1. Total height, 84 ft., 8 in.
2. Packed height, 66 ft., 3 in.
3. Clearing sections
  - a. Top, 3 ft., 6 in.
  - b. Bottom, 8 ft., 3 in.
4. Diameter of column, 22 in.
5. Feed positions (height from bottom of column)
  - a. Furfural, 80 ft., 10 in.
  - b. Oil, 32 ft., 8 in.
  - c. Naphtha reflux, 7 ft., 10 in.
6. Phase interface position—from 23 ft., 5 in. to 30 ft., 5 in. from bottom of column.
- 45 7. Condition of operation column 10.
  - a. Rates

Feed	Gals./hr.	Ratio to Feed Oil
Furfural	250-350	5-1
Oil	50-70	
Naphtha Reflux	15-21	0.3-1

b. Temperatures

- (1) Top of column, 107 to 115° F.
- (2) Bottom of column, 103 to 108° F.
- (3) Furfural feed, 108 to 115° F.
- (4) Oil feed, 105 to 110° F.

b. Temperatures

- (1) Top of column, 64 to 78° F.
- (2) Bottom of column, 58 to 65° F.
- (3) Extract solution, 65 to 80° F.
- (4) Naphtha, 58 to 65° F.

C. Quality of feed oils used

The oils used in these runs were degummed soya oil whose constants fell within the following ranges:

Iodine value, 129.3 to 137.3
 Per cent free fatty acid, 0.28-0.99
 Color (Gardner), 9½ to 10½
 Per cent chlorophyll, .00014-.00034
 Per cent carotene, .004-.0068

D. Quality of products produced

	Extract	Raffinate	By-Product
Per Cent Yield.....	26.2-37.8	61.3-72.5	0.7-1.3
Iodine value.....	151.4-153.0	123.8-126.3	137.9
Per cent free fatty acid.....	0.2-0.8	.04-.075	16.2
Per cent tocopherol.....			2.5
Per cent unsaponifiable matter.....			7.89

A second apparatus of slightly different character is indicated diagrammatically in Fig. 2. This apparatus comprises two columns which may be conveniently arranged with respect to each other. The first column 21 is provided near its upper extremity, with an inlet 22 for polar solvent such as furfural, and it is provided near its lower extremity with an inlet 23 for the glyceride oil to be treated. The inlets 22 and 23 are spaced from the extreme ends of the column a sufficient amount to admit of the proper solution separation before the solutions are withdrawn, e. g. 5 to 15 feet. The raffinate passes out at the top of the column as indicated at 24, the exact is drawn off at the bottom as indicated at 26. The extract comprising a fraction of oil of increased unsaturation, may be withdrawn and passed to the upper extremity of a second column 27, constituting a reflux zone. The feed and flow is appropriately maintained and controlled by the valve indicated diagrammatically at 29.

A reflux of naphtha is introduced near the lower extremity of column 27, through a line 38. The furfural solution or polar solvent extract containing most of the free fatty acids, sterols and highly unsaturated glycerides, is drawn off at the bottom of the column, as indicated at 31. The naphtha extract containing some of the glycerides initially withdrawn in the furfural solution, passes from the top of the column as indicated at 32. This solution is returned to the bottom of the column 21 at a point somewhat above the bottom thereof, so that the glycerides associated therewith, are returned to the column 21 and subjected to further fractionation. The raffinate solution passes out of column 21 at 24, and the solvent may be removed from the oil by distillation.

The furfural glyceride oil-by-product mixture

from line 31 may be discharged into the upper part of a third column 33, where nearly all of the glycerides, e. g. 95% of those present in the extract solution, are extracted out by an upwardly flowing current of naphtha introduced at 34 near the bottom of the column. Highly unsaturated extract oil dissolved in naphtha, is drawn off at 36 at the top of the column. By-product and a minor amount of glycerides are drawn off at 37 near the bottom of the column. The solvents may be evaporated or steam stripped from the fractions obtained at 36 and 37. It is to be understood that all of the columns 10, 16, 21, 27 and 33 as herein disclosed, may be packed or provided with Berl saddles, Raschig rings, re-distribution plates or other means for effecting intimate and uniform contact with polar solvent, naphtha and oil, without channeling or separation into streams. That is, the phases should permeate through each other, probably as fine droplets but without such emulsification as would prevent phase separation and would eliminate the phase interface. Before or after the evaporation of the solvent, the resultant glycerides of relatively highly unsaturated nature, may be subjected to any desired technique such as further bleaching or treatment, to remove any residual anti-oxidants which may be retained and concentrated therein as a result of the various extraction operations to which the oil is subjected.

In a specific example, soybean oil containing chlorophyll and other naturally occurring pigments, free fatty acids, sterols, etc., was fed in at the inlet of the column 21 shown in Fig. 2 through line 23, in a proportion of 25 parts by volume. The column 21 was maintained at 111° F. The furfural was introduced through line 22 in a proportion of 125 parts by volume.

Furfural extract solution containing oil of increased iodine value was taken off at 26 and passed to the column 27 slightly below the upper extremity thereof. Column 27 was also maintained at about 111° F. A reflux of naphtha comprising aliphatic hydrocarbons averaging about 9 carbon atoms and free of or nearly free of aromatics, was introduced into the system as indicated at 30 in a proportion of 10 parts by volume. A raffinate solution containing moderately saturated glycerides was withdrawn at 32 from the column 27 in a proportion of 15 parts by volume, and was then returned to the column 21 and subjected to further fractionation. The extract solution from column 27 could be backwashed with naphtha in column 33.

The glyceride oil was initially of an iodine value of approximately 130. This value, of course, will vary somewhat with the source of the oil and the particular season in which it is produced. Usually it will be 130 to 135.

As a result of the treatment above described, there was obtained an extract oil passing out in solution with the furfural at 31 from the column 27. This extract constituted 33.8% of the total oil and had an iodine value of 146.4. The raffinate passing out at 24 from column 21 constituted 66.2% and had an iodine value of 121.2.

Cottonseed oil could be substituted for soybean oil in the foregoing examples. A temperature of 118° F. in column 10 would be at or near the optimum, 70° F. in column 16 could likewise be employed. A reflux ratio of .1 to .5 based upon oil input is contemplated.

Similarly linseed oil could be substituted. The

column 10 may be at 80° F. A reflux of .1 to .5 could be employed.

With either cottonseed oil or linseed oil, the ratios of oil to furfural may be those previously specified for soybean oil.

The forms of the invention described are to be regarded as being by way of example only. It will be apparent to those skilled in the art that numerous modifications may be made therein without departure from the spirit of the invention or the scope of the appended claims.

I claim:

1. A process of obtaining a fraction of glyceride oil of high iodine value, good color and relatively low free fatty acid content, from an oil of low iodine value containing substantial amounts of the foregoing impurities, which method comprises the steps of counter-currently flowing the oil to furfural by introducing furfural into an upper part of an elongated extraction zone, and oil into the same extraction zone at a point below the point of introduction of furfural, then further introducing a reflux of naphtha at a point below that of introduction of the oil in an amount and at a temperature to obtain a furfural extract solution comprising 10 to 70% of the oil, withdrawing the furfural extract solution at the bottom of the extraction zone, then further extracting at least 95% of the glycerides of the oil from the furfural extract solution with naphtha, in a second extraction zone and evaporating the naphtha to recover the fraction.

2. A process of obtaining a fraction of a glyceride oil of high iodine value, good color and relatively low free fatty acid content from a low iodine value oil and containing coloring matter and free fatty acids, which method comprises countercurrently extracting the oil with three to eight volumes of furfural per volume of oil, in an elongated extraction zone in which the furfural is introduced near the top, and the oil at a point below the point of introduction of the furfural, and .1 to 1.0 volumes of naphtha is introduced at reflux at a point below the introduction of the oil, whereby to obtain a furfural extract solution constituting 10 to 70% of the original oil of oil high in iodine value and by-products, withdrawing said extract solution from the extraction zone at a point near the bottom thereof, and extracting the glycerides from the furfural solution by counter-currently flowing the solution against naphtha in a second zone, the naphtha being in a proportion of 2 to 5 volumes per volume of original oil and evaporating the naphtha to recover the fraction.

3. A process as defined in claim 1 in which the oil treated is soybean oil.

4. A process as defined in claim 2, in which the temperature of the second zone is 10 to 60° F. lower than that of the first.

5. A process as defined in claim 1, in which the oil treated is degummed soybean oil.

6. A process as defined in claim 2, in which the oil treated is degummed soybean oil.

7. In a process of obtaining a fraction of soybean oil of high iodine value, good color and low fatty acid content from a low iodine value soybean oil containing coloring matter and free fatty acids, the steps which comprise introducing the oil into the middle portion of an extraction zone, introducing furfural at the top of the zone and naphtha as a reflux at the bottom of the zone, the furfural being in a proportion of 3 to 8 volumes per volume of oil, the naphtha as reflux being in a proportion of .1 to 1.5 volumes per volume of oil, the extraction zone being maintained at a temperature of 90 to 120° F., withdrawing at the top of the extraction zone naphtha and raffinate oil of low iodine value, withdrawing at the bottom of the extraction zone an extract solution of oil of high iodine value, free fatty acids and coloring matter in furfural, then passing the extract solution to the top of a second extraction zone and introducing naphtha at the bottom of said zone, the ratio of naphtha being from 1 to 5 volumes per volume of original oil, the temperature of the second extraction zone being within a range of 60 to 80° F. whereby to obtain a naphtha solution of the glycerides of low free fatty acid content and coloring content and to leave in solution in the furfural not more than .3 to 1.5% of the original oil, then evaporating the naphtha solution to obtain said fraction.
